UNITED STATES PATENT OFFICE.

ERIK ANTON RUNDLÖF, OF STOCKSUND, SWEDEN.

CONTROLLING DEVICE FOR FLUID-PUMPS IN INTERNAL-COMBUSTION ENGINES.

1,189,741.

Specification of Letters Patent.

Patented July 4, 1916.

Application filed October 20, 1913. Serial No. 796,246.

To all whom it may concern:

Be it known that I, ERIK ANTON RUNDLÖF, a subject of the King of Sweden, residing at Stocksund, in the Kingdom of Sweden, have invented new and useful Improvements in Controlling Devices for Fluid-Pumps in Internal-Combustion Engines, of which the following is a specification, reference being had to the drawing accompanying and forming part hereof.

My invention relates to controlling devices for fluid pumps intended for internal combustion engines of the class in which the pump piston or pistons is or are actuated by a reciprocating member.

The object of the invention is to effect control of the stroke of the pump.

The invention is mainly characterized by this that between the reciprocating part and the piston or pistons is placed a member against which the piston or pistons press, the said member, in order to effect control of the stroke of the pump, being movable.

In the accompanying drawing a constructional form of the invention is illustrated.

1 designates the pump cylinder provided with the suction conduit 2 and the pressure conduit 3, 4 is the pump piston moved outward by a spring 5 so as to press against one arm 6 of a bell crank lever 6, 10 fulcrumed on a pivot 9 or the like, 7 is the reciprocating member supported by the sliding plane 8. The arm 10 of the bell crank lever rests against an eccentric 11 journaled in a stationary part of the pump construc-

tion and to the shaft 12 of which is attached an arm 13 connected to a rod 14. Upon turning of the eccentric 11 the bell crank lever swings and causes the piston 4 actuated by the spring 5 to move outward to a greater or smaller extent, so that the stroke of the pump accordingly becomes longer or shorter. The arm 6 pressing against the piston 4 will be hit by the member 7. Said member 7 operates as a hit or miss controller, for instance by sliding on a plane 8 provided with a slanting part, in which case the member 7, owing to said slanting part, hits or misses the arm 6 provided for this purpose with an aperture 15 into which the member 7 in the last named case can enter.

The eccentric 11 need not necessarily be rotatable always but may be fastened in certain adjusted positions by means of nuts 55 or in some other suitable manner.

I claim:

In a fluid pump for internal combustion engines, the combination of a reciprocating pump piston, a hit or miss device actuating said piston, a bell crank lever one arm of which is located between the piston and the hit or miss device, and an eccentric actuating the other arm of said lever, substantially as and for the purpose set forth.

ERIK ANTON RUNDLÖF.
